UNITED STATES PATENT OFFICE.

EDWARD J. HOWARD, OF NEW YORK, N. Y., ASSIGNOR TO EDWARD W. BRUNSEN AND FRED S. SWEET, OF PROVIDENCE, RHODE ISLAND.

TOY GUN.

SPECIFICATION forming part of Letters Patent No. 716,547, dated December 23, 1902.

Application filed June 12, 1902. Serial No. 111,362. (No model.)

To all whom it may concern:

Be it known that I, EDWARD J. HOWARD, a citizen of the United States, residing at New York, in the county of New York and State 5 of New York, have invented certain new and useful Improvements in Toy Guns, of which the following is a specification, reference being had therein to the accompanying drawings.

Like letters indicate like parts.

Figure 1 is a perspective view of my improved toy gun in action. Fig. 2 is a side elevation of the same. Fig. 3 is a longitudinal section on line $\alpha\alpha$ of Fig. 2. Fig. 4 is a 15 partial view of my invention as seen on line $\alpha\alpha$ of Fig. 2 when the loose outer sleeve is in contact with the fixed collar. Fig. 5 is a perspective view of the powder cracker used as the explosive charge of my improved toy gun. Fig. 6 is a perspective view of the soft-rubber ball which serves as a missile. Figs. 7 20 and 8 are perspective views illustrating modified forms of the handle of the toy gun. Fig. 9 is a view showing a modified form of the 25 means for closing the fuse-aperture of the barrel of said toy gun.

My invention relates to toy guns; and it consists of the novel construction and combination of the several parts, as hereinafter 30 described and specifically set forth in the claims.

A is a continuous tube or barrel made of pasteboard, sheet metal, or other suitable material. A block B, made of wood or other 35 proper substance, is inserted and secured in position within the bore of the tube A, at one end thereof, as best shown in Fig. 3. A fixed collar C surrounds the tube A. The tube A is open at its outer end, as shown in Fig. 3, 40 and constitutes the barrel of the toy gun. It is provided with a small slot or aperture, as seen in Figs. 3 and 4, preferably rectangular in shape and located a short distance above the inner end of the block B. A loose sleeve 45 or collar D fits rotatably on the barrel A and is made with a small slot or aperture b, which when the sleeve or collar D is in the position shown in Figs. 2, 3, and 8 registers with the slot α of the barrel A, being preferably of 50 the same shape and size. When the slots α and b so register, the lower edge of the sleeve

or collar D is separated a short distance from the upper edge of the fixed collar C, as seen in Figs. 2 and 3.

A powder cracker E, having the usual fuse 55 c, is inserted through the slots b and α into the interior of the barrel A, as illustrated in Fig. 3, the fuse c protruding from said slots, as there represented.

A soft hollow rubber ball F (having the 60 usual air-hole d, as seen in Fig. 3) has such a diameter as to snugly fit in the bore of the barrel A, within the open end thereof, and should be pressed down therein. The sleeve or collar D is then moved down the barrel A 65 until its lower edge abuts the upper edge of the fixed collar C, and at the same time it is slightly rotated, the result of these movements being that the sleeve D, acting as a valve, almost closes the slot α of the barrel 70 A, leaving only a very small aperture, as shown in Figs. 1, 4, and 7, through which aperture the loose end of the fuse c of the powder cracker E freely extends. In Fig. 1 the 75 relative positions of these slots α and b are represented, the former being indicated by dotted lines.

By applying a slow match or otherwise igniting the freely-extending end of the fuse c of the powder cracker E the explosion of the 80 powder cracker is caused in the confined space or chamber within the barrel formed between the inner end of the block B and the ball F. As the almost complete covering of the slot α of the barrel A by the sleeve D 85 practically closes that vent, the whole force of the combustion-gases resulting from the explosion of the powder cracker is exerted in expelling the ball F, which being thus forcibly driven out of the barrel A is projected to 90 a considerable distance. When the ball F has thus been expelled from the barrel A, the parts of the cracker E remaining after the explosion will fall out of said barrel when the latter is inverted.

The collar C is fixed in its position upon the tube A, as shown, and constitutes a stop to limit the downward movement of the loose collar or sleeve D and also serves as a finger-guard to prevent the sliding of the hand too 100 near the burning fuse c.

Instead of having a straight handle made

up of the lower end of the tube A and the inserted block B a more convenient shape may be given to the handle, adapting it to the hand, as shown at G in Fig. 7, or the handle 5 may be formed into the shape of the butt of a pistol, as shown at H in Fig. 8.

The loose sleeve or collar D may be dispensed with, if desired, and a cover e may be pivotally mounted on the barrel A, as illustrated in Fig. 9, which will serve to partially close the aperture a of the barrel A for the purpose already explained.

The soft-rubber ball is easily compressed so as to serve as a wad in the barrel A, and 15 thus to confine the combustion-gases resulting from the explosion of the charge until they have reached the proper intensity of force to expel the ball. This ball being soft is harmless in its effects and cannot break, 20 injure, or damage anything it strikes.

This implement constitutes an attractive toy for use in the celebration of Independence day and on other festive occasions.

I claim as a novel and useful invention and 25 desire to secure by Letters Patent—

1. The improved toy gun herein described, consisting of a tube or barrel having an ap-

erture through one side thereof, a handle inserted in and closing one end of said tube, and a collar or sleeve loosely mounted on said tube and provided with an aperture registering with the aperture of said tube, which loose collar or sleeve is capable of movement to partially cover the first-named aperture, substantially as shown and for the purpose 35 specified.

2. The improved toy gun herein described, consisting of a handle, a barrel provided with an aperture through its side, which barrel is mounted on said handle and has its inner end closed, a fixed collar upon the exterior of said barrel, and a collar loosely mounted on said barrel and provided with an aperture adapted to register with the first-named aperture, which loose collar or sleeve is movable into contact with said fixed collar and so to partially cover the first-named aperture, substantially as specified.

In testimony whereof I affix my signature in presence of two witnesses.

EDWARD J. HOWARD.
